DESIGN FOR A WINDOW CORNICE OR SIMILAR ARTICLE

Sylvia G. Cline, Chicago, Ill.

Application August 9, 1947, Serial No. 140,802

Term of patent 14 years

(Cl. D21—6)

To all whom it may concern:

Be it known that I, Sylvia G. Cline, a citizen of the United States and a resident of the city of Chicago, county of Cook, and State of Illinois, have invented a new, original, and ornamental Design for a Window Cornice or Similar Article, of which the following is a specification, reference being had to the accompanying drawing, forming a part hereof, in which:

Fig. 1 is a front elevational view of the window cornice, showing my new design,

Fig. 2 is a top plan view of the window cornice, and

Fig. 3 is a side elevational view thereof.

I claim:

The ornamental design for a window cornice or similar article, as shown.

SYLVIA G. CLINE.
